SNOWMOBILE

Anthony D. MacKeen, Valcourt, Quebec, Canada, assignor to Bombardier Limited, Valcourt, Quebec, Canada

Filed Oct. 6, 1969, Ser. No. 19,431

Term of patent 14 years

Int. Cl. D12—13

U.S. Cl. D14—24

FIG. 1.

FIG. 2.

FIG. 3.

FIG. 4.

FIG. 1 is a perspective view from the top, and one side of the snowmobile showing my design.

FIG. 2 is a side elevation view thereof.

FIG. 3 is a front elevation thereof.

FIG. 4 is a fragmentary plan view of the back thereof.

The side opposite to that shown in a mirror image thereof. The back of the lower panel is open.

I claim:

The ornamental design for a snowmobile, as shown and described.
